UNITED STATES PATENT OFFICE

2,359,804

WOMAN'S GARMENT

George H. Struthers, Flushing, N. Y., assignor to
 Sears, Roebuck and Co., Chicago, Ill., a corporation of New York

Application January 23, 1941, Serial No. 375,639

3 Claims. (Cl. 2-67)

My invention relates to garments for women, and has to do more particularly with an improved brassière which may be used in combination with other garments of feminine wearing apparel, such as bathing suits, dresses, slips, etc.

A particular object of my invention is to provide an improved brassière which may be detachably secured in and to another garment and may be readily detachable therefrom for separate laundering or for use in another garment, if desired.

Another object is to provide such an improved detachable brassière which will be simple in construction, which will impart to the bust the so-called molded or "up-lift" contours at present in vogue, and which, in general, will be entirely satisfactory for the purposes desired.

In the preferred embodiment of my invention, these objects are attained by forming a brassière of the type referred to of a material which is elastic in one direction and substantially inelastic in its transversed direction and is so cut and arranged as to take the maximum advantage of these characteristics, i. e., so that yielding and non-yielding pressures, respectively, may be applied to the bust in different directions whereby the maximum molding effect may be obtained while securing elements are provided for detachably anchoring the brassière to an outer garment.

Various other objects and advantages will become apparent as the description proceeds.

Referring now to the drawing forming a part of this specification and illustrating a preferred form of my invention:

Fig. 1 is a back elevational view of a bathing suit to which has been applied a brassière embodying my invention;

Fig. 2 is a section-elevation taken substantially along the line 2-2 of Fig. 1 and showing a portion of my improved brassière on an enlarged scale; and

Fig. 3 is a plan view of my improved brassière in open position and detached.

Referring first to Fig. 3, my improved brassière comprises a border portion formed of relatively inelastic material, such as bias tape or the like, and comprising a bottom border 10, side border portions 12, 12, the latter being outwardly curved or angular, and a V-shaped neck border portion 13.

Elastic tapes 15 are secured in a continuation of bottom border 10 and similar elastic tapes 16, 16 are secured in a continuation of the upper side border strips 12, the ends of these elastic

tapes 15 and 16 being secured together as at 17, 17. At these apices 17, 17 suitable securing elements, as for example snap fasteners 20, are provided. At the top apices 22, 22, or meeting points of the border strips 12 and 13, like attaching elements 20' are also provided.

Within the border strips are secured cup-shaped bust receiving portions 25, 25, these two portions being preferably formed of two separate pieces of material seamed together as at 26. I preferably employ for these portions a material which is relatively elastic in one direction and relatively non-elastic in the direction at right angles to the one first mentioned. Various textile materials meet this description but I prefer to use a relatively light weight so-called "jersey" material knitted from a suitable fiber, such as artificial silk or any other suitable textile fiber. This material is cut in such a way that it is stretchable along the lines indicated by the arrows XX while being substantially inelastic in a direction perpendicular to these lines.

Each of the cup-shaped portions is formed from the lower part of a blank from which a substantial V-shaped portion has been cut, the sides forming the V-shaped opening being then joined along the seams 30, 30.

Along the lower edges 32, 32 of the cup-shaped portions 25 is secured a strip of material 35 similar to that of the cup-shaped portions, said strip 35 being so arranged that it is stretchable in a vertical direction as indicated by the arrows YY.

It will be seen that the brassière described above provides a molding effect on the bust by reason of the stretchable nature of the material in an up and down direction. Because of its being non-yielding in a transverse direction, adequate support and confining effect is obtained, the breasts being firmly retained upwardly and separated.

The stretchable nature of the elastic tapes 15 and 16 enables the brassière to adjust itself in a lateral direction according to the varied proportions of the individual's anatomy.

The brassière just described may be detachably secured in any suitable garment. As shown in Fig. 1, it is attached to a bathing suit. It will be readily understood that the brassière, if desired, may likewise be detachably secured to any other garment which will provide adequate support therefor, such as, for example, a dress, slip, blouse or waist, etc.

Referring to Fig. 2, it will be seen that the bathing suit there illustrated, which, as pre-

viously stated, might be any other suitable type of garment, comprises, roughly speaking, an upper or bodice portion 40 and a lower or skirt portion 45. The bodice portion is formed to include a pair of cup-shaped portions 42, 42, which may be similarly shaped to the cup-shaped portions 25 of the brassière. It is highly desirable, especially in the case of a bathing suit, that this bodice portion be likewise formed of so-called "one-way stretch" material, although, of course, it is quite feasible that the entire bathing suit be formed of the same kind of material. This material is at present obtainable on the market in many attractive colors and finishes, one embodiment being known as Lastex and when employed for bathing suits having an attractive satin-like plain or printed outer surface. In any event, the cup-shaped portions 42, 42, of the bodice are preferably formed similarly to the corresponding portions of the brassière so as to provide resilience or stretch in an up and down direction without any substantial yielding in a transverse or horizontal direction. The brassière is secured by means of suitable cooperating fastening elements such as eyelets (not shown) receiving the snaps 20 and placed at the apices 43, 43, of the cup-shaped portions 42, 42, and also at points adjacent the rear and sides of the waist 46.

The skirt portion 45 is preferably made of the same kind of material as the bodice 40, and if made of such "one-way stretch" material, is cut in such a way that the yielding will be lateral rather than up and down. In this way the lower portion will yield to accommodate itself to hips of different proportions and will thus form a snug and trim fit.

Shoulder straps 47 of any suitable design may be provided, and, of course, it will be readily understood that the garment may be cut according to a wide range of styles or designs to provide different retaining means as well as different esthetic effects without departing from the spirit of my invention.

Various modifications may suggest themselves to those skilled in the art without departing from the spirit of my invention, and, hence, I do not wish to be restricted to the specific form shown or uses mentioned, except to the extent indicated in the appended claims.

I claim:

1. In combination with a woman's garment including a bodice, a brassière detachably secured in said bodice, said brassière comprising individual bust-containing pouches, a continuous strap connected to and coextensive with and depending from the lower edges of said pouches and formed to lie flat against the wearer immediately below the bust, the lower margin of said strap being substantially horizontal, elastic tape means secured to said lower margin and extending substantially horizontally beyond both ends thereof, elastic tape means joined to the outer ends of the aforesaid elastic tape means and to side portions of the respective pouches, and detachable fastening means at the upper portions of said pouches and at the junctures of said tape means, cooperating with complementary fastening means in adjacent portions of said bodice, said strap and each of said pouches being relatively yieldable in an up-and-down direction and relatively non-yieldable in a lateral direction.

2. In combination with a women's garment including a bodice, a brassière including individual bust-containing pouches and a continuous strap connected to and transversely coextensive with and depending from the lower edges of said pouches and formed to lie flat against the wearer immediately below the bust, said strap and each pouch being relatively yieldable in an up-and-down direction and relatively non-yieldable in a lateral direction, detachable fastening means at the upper portions of the pouches engageable with cooperating means at the upper portions of the bodice, and detachable fastening means connecting said strap to the bodice adjacent the waistline thereof.

3. In combination with a woman's garment including a bodice, a brassière including individual bust-containing pouches and a continuous strap connected to and transversely coextensive with and depending from the lower edges of said pouches and formed to lie flat against the wearer immediately below the bust, detachable fastening means at the upper portions of the pouches engageable with cooperating means at the upper portions of the bodice, and detachable fastening means connecting said strap to the bodice adjacent the waistline thereof.
